UNITED STATES PATENT OFFICE.

ERASMUS HELM, OF BROOKLYN, NEW YORK.

BED-COVERING HOLDER.

Application filed July 1, 1926. Serial No. 119,952.

This invention relates to bed covering holders.

As is well known, blankets and other bed covering shifts and fails of its purpose due 5 to restlessness of the user or for other reasons moves from over portions of the user and sometimes moves entirely off the bed, exposing the user to cold and in the case of babies particularly, it has been found expedient to provide means of some kind for preventing the uncovering of the babe, and 10 in the present instance it has been found desirable to do away with the use of safety pins because of the danger of injury to the 15 user in the event of accidental unfastening of the safety pins.

It is another object of the present invention to provide an exceedingly simple, durable, efficient and inexpensive device which 20 may be readily applied to the bed covering at any point or at various points, for the purpose of preventing the dislocation in part or entirely of the bed clothing with relation to the bed.

25 With the above and other objects in view, the invention consists in the construction and novel combination and arrangement of parts hereinafter fully described, illustrated in the accompanying drawings and 30 pointed out in the claims hereto appended, it being understood that various changes in the form, proportion and minor details of construction, within the scope of the claims, may be resorted to without departing from 35 the spirit of the invention or sacrificing any of the advantages thereof.

In the drawings:—

Fig. 1 is a top plan view of the invention showing its application;

40 Fig. 2 is a sectional view taken longitudinally through the holder;

Fig. 3 is a top plan view of the button used with the holder; and

45 Fig. 4 is a transverse sectional view of the button showing the application of the loop of the holder to the button to secure the covering.

50 Referring now more particularly to the accompanying drawings, the reference character 5 indicates a portion of a bedstead and 6 indicates a blanket or other bed covering which is secured against accidental removal from its normal position through the instrumentality of my improved holder, indicated 55 generally by the reference character A.

The holder consists preferably of a narrow elastic or other flexible strip 7 provided with pairs of perforations 8 and at one end having a loop 9 having a contracted outer end adapted to fit over a removable 60 button 10 applied to the under side of the covering 6 so that the covering at the point of connection of the loop 9 with the button may envelope or embrace the button as the contracted outer end of the loop 9 is drawn 65 over the button in a manner which is readily understood.

To fasten the holder to the bedstead, I provide tie cords or the like, 11 and 12. These tie cords have their inner ends passed 70 through corresponding perforations 8 in the strip 7 and tied therein, as at 13 and 14, respectively. The outer ends of these tie elements embrace a part of the bedstead and are knotted as at 15, whereby a ready 75 application of the holder to the bedstead and covering may be effected and whereby also a ready disconnection of the holder from the bedstead may be made in order to remove the covering. While the holder has 80 detachable connection with the covering 6 it is clear that by unfastening the tie elements 11 and 12 at the knotted end 15 the holder need not be removed from the covering 6, whether the covering be folded and 85 put away or temporarily removed for airing or other purposes.

While I have shown but one of the holds 90 A, this being deemed sufficient for purposes of illustration, it is understood that as many of these holders may be employed as may be desired, and it is believed that the illustration is sufficient to show the application of the holder and from the disclosure made it is clear that an inexpensive 95 holding device is produced for the purpose hereinbefore stated and one which may be easily and readily applied or removed, and which is purchasable at relatively small expense and usable without danger of injury 100 to the user.

The spaced pairs of perforations 8 permit of adjustment of the elements 11 and 12 because the inner ends thereof may be secured interchangeably in the different 105 pairs of perforations.

What is claimed is:—

1. A bed covering holder comprising an elastic strip provided with spaced pairs of perforations and at one end having a loop 110

to engage a button applied to the covering, and flexible means adapted to embrace a part of a bedstead and including ends passed through pairs of perforations of the said strip interchangeably and knotted to prevent withdrawal from the perforations, whereby to secure the covering to the bedstead.

2. A bed covering holder comprising an elastic strip provided with perforations and

at one end having a loop to engage a button adapted to be applied to the covering, and tie elements passed through the perforations and tied at their inner ends to the strip and adapted to be passed around a part of a bedstead and tied together, whereby to secure the covering to the bed.

In testimony whereof I have hereunto set my hand.

ERASMUS HELM.
